UNITED STATES PATENT OFFICE.

WILLIAM F. KIESEL, JR., OF ALTOONA, PENNSYLVANIA.

LOCOMOTIVE TENDER.

Application filed December 24, 1925. Serial No. 77,567.

This invention relates to locomotive tender construction and more particularly to improvements in the underframe and the tank.

It is the general object of the present invention to provide a novel and improved locomotive tender in which the design is materially simplified, the weight reduced and the cost of construction lowered.

More particularly it is an object of the present invention to provide a locomotive tender underframe composed of a single casting forming only a center sill for supporting the tank.

Another object of the present invention consists in the provision of a locomotive tender underframe formed of a single casting comprising a center sill, draft gear pocket, front draw bar fulcrums, center-plates and side bearing support arms.

Still another object of the present invention consists in the provision of a locomotive tender underframe formed as a single unitary casting combining all of the parts necessary; for supporting the tank, receiving the draft rigging, cooperating with the trucks, supporting the brake cylinder and performing all of the various functions usually performed by a complex fabricated underframe.

A further object of the present invention consists in the provision of a tender tank adapted to be supported by and secured to a single center sill without the provision of side sills, end sills or full-width body bolsters.

A still further object of this invention comprises the forming of a tender tank provided with internal bracing so arranged as to support the entire load of the tank and contents from a single center sill, provision being made to utilize the side plates of the tank as longitudinal vertical girders.

Another and further object of the present invention consists in providing a tender underframe formed as a single unitary casting without end or side sills and so arranged as to receive a tank constructed either for use with an automatic stoker or without such a stoker.

Heretofore it has been the almost universal practice in the construction of locomotive tenders to provide an underframe for the support of the tank which includes side sills, end sills and usually a center sill, together with body bolsters extending from the center-plates. The construction of such a frame

combined with all attachments and brackets for auxiliary equipment is too complex to be readily made in the form of a single casting, and therefore it must be fabricated either from rolled sections or from a number of separate castings, involving a plurality of machine operations and considerable riveting and bolting. With such a construction there is always the possibility of the failure of certain of the fastenings. At the same time the cost of construction is materially increased due to the attendant difficulties in constructing such a frame. It has heretofore been presumed that side sills and end sills were necessary to properly support and reinforce the tank to prevent the same from sagging under its great load of water which is particularly susceptible to shifting and surging on rough tracks, when rounding curves and when going up and down grade.

The present invention has for its object the elimination not only of the side sills, but also of the end sills, and a material reduction in the length of the body bolsters, thus reducing the frame to a single center sill with short projections from the center-plate supports to carry the side bearings, which projections act as short body bolsters to assist in the support of the tank. With this simple construction, the frame can be made as a unitary casting in the form of a box girder, the sides and bottom of which may be provided with a plurality of openings for the sake of lightness without materially impairing the strength of the same. Such an underframe can be made by a comparatively simple casting operation, and the amount of machining is reduced to a minimum. At the same time, the weight is very materially reduced, thus allowing for lighter trucks and running gear. In forming the underframe as a single casting, it has been found possible to combine in this casting, in addition to the parts already mentioned, the draft gear pocket, the front draw bar fulcrums, the center-plate supports, the center-plates, the tank end stops and the brake cylinder attaching means. For use on railroads which scoop water while the engine is in motion, the necessary additional parts for the support of the scoop and its pneumatic operating cylinder and associated devices can be incorporated as a unitary part of the casting.

The tank for use with the above described underframe must be of special construction.

It is substantially rectangular in cross section, following generally the conventional external shape and is internally braced so as to transfer the load, which is almost uniformly distributed over the bottom of the tank, entirely to the center sill, center-plate supports and side bearings support arms. In so doing the tank side plates are caused to act as longitudinal, vertical girders which, by reason of their extreme depth, are quite efficient for this purpose. In addition to the above reinforcing and bracing means, the slope sheet is extended and riveted to the side plates or girders, thus forming in effect a transverse girder to prevent sagging of the sides of the tank which is supported at the bottom only along its longitudinal center. The arrangement and bracing of the tank is of extreme importance, for it is only by the use of such bracing that side sills, end sills and other parts can be eliminated to thus save a large amount of metal and weight.

Other and further objects of the present invention will be disclosed and more fully discussed in the following specification and accompanying drawings wherein is shown a single exemplary embodiment of the present invention with the understanding, however, that various changes may be made therein without departing from the spirit of the invention or the scope of the appended claims.

In said drawings:

Figure 1 is a plan view of a complete tender constructed according to the present invention;

Figure 2 is a right side elevation thereof;

Figure 3 is a longitudinal vertical section through the center of the tank, the underframe being shown in elevation;

Figure 4 is a transverse vertical section on line 4-4 of Fig. 3, looking toward the rear;

Figure 5 is a similar section on the line 5-5 of Fig. 3;

Figure 6 is a similar section on the line 6-6 of Fig. 3, the frame being omitted;

Figure 7 is a view similar to Fig. 6 on the line 7-7 of Fig. 3;

Figure 8 is a plan view of the front end of the underframe;

Figure 9 is a plan view of the rear end of the underframe;

Figure 10 is a partial horizontal section on the line 10-10 of Fig. 3, showing the means of securing the forward end of the tank to the underframe;

Figure 11 is a partial longitudinal vertical section on the line 11-11 of Fig. 10;

Figure 12 is a partial longitudinal vertical section on the line 12-12 of Fig. 10;

Figure 13 is a partial transverse vertical section on the line 13-13 of Fig. 11;

Figure 14 is a partial plan view of the

rear end of the tender with the tank broken away to disclose the rear end step beam gussets;

Figure 15 is a partial longitudinal vertical section on the line 15-15 of Fig. 14, 70 showing the rear tank securing means;

Figure 16 is a partial longitudinal vertical section, showing the means of securing the front end of the tank to the underframe on tenders adapted for hand firing; and 75

Figure 17 is a partial transverse vertical section on the broken line 17-17 of Fig. 16.

Figures 1, 3, 7, 10, 11 and 12 refer to a tender provided with an automatic stoker, whereas Figures 16 and 17 refer to a tender 80 adapted for hand firing, and the remaining figures are generic to both types.

The underframe disclosed in the drawings is adapted without substantial modification for use either with a tank provided 85 with an automatic stoker or with a tank intended for hand firing of the locomotive. The essential features of each tank are the same, there being but a slight difference 90 in the front end fastening means and in the provision, in one, of a pocket to receive the stoking apparatus, which pocket, in the hand firing type is replaced by water spaces joined to the main portion of the tank. The space necessary for the automatic conveyer 95 screw of the stoker is somewhat longer than the usual shovel plate adapted for hand firing, and hence in the two types of tanks the sections illustrated by way of example in the drawings may be somewhat displaced longitudinally of the tender, but are otherwise identical. 100

The underframe, which is substantially identical in construction for both the stoker and non-stoker types of tank, will be first 105 described. Referring to the drawings, it will be seen that this underframe 20 is a one-piece casting having the general form of a box girder, slightly longer than the tank which it is adapted to support. It is provided with the front and rear center-plate supports or carriers 21 and 22, each having a center-plate 23 on its bottom to engage with the corresponding truck bolster and to be secured thereto by the usual kingpin (not shown). At the forward end there are provided the front draw bar fulcrums 24 cast integral with the underframe and adapted to receive the usual draft gear rigging of any suitable form and the chafing plate 25. At the rear end there is the pocket 26 to receive any conventional type of draft rigging. The style of draft apparatus used at either end forms no part of the present 110 invention, and will not be further described here, for the invention is only concerned with forming the pockets, to receive these two draft gears, as an integral part of the underframe. Between each draft gear pocket and the adjacent center-plate sup- 115

port, there is but a section 27, 28 of the single center sill which is in the form of a hollow box girder substantially rectangular in cross section with the walls of the proper thickness to provide adequate strength against the bending load resulting from the weight of the tank and its contents, and also to provide sufficient strength for the tension and thrust loads attendant upon the drawing and stopping of the tender and the train connected to the rear of it. If desired, suitable openings such as 29 and 30 may be provided in the upper and lower plates of the sill for the purpose of lightening them where this can be done without reducing their strength.

Between the center-plate supports, there is also but a single center sill which is likewise in the form of a box girder provided with various lightening apertures 31, 32, 33 and 34 in its upper plate. The upper plate is also provided, to the rear of the front center-plate support, with the tank end stops 35 cast integral therewith and projecting vertically upward for a purpose to be hereinafter described. These tank end stops are not used when the underframe supports a tank of the non-stoker type and can therefore be left off. In the case of non-stoker tanks, the tank front end stop is formed by the shoulder or abutment 36, best shown in Figs. 3 and 8, which abutment is formed by raising the forward end of the sill to incorporate in it the front draw bar fulcrums.

The lower plate of the center sill is provided at 37 with the lugs 38 and the slots 39, the former serving to position the brake reservoir 40 and the latter to receive the brake reservoir straps 41 for securing the reservoir to the frame. The center sill forwardly of the brake reservoir attaching lugs, may be provided with the bosses or lugs 42 for attaching the water scoop, where the tender is adapted for use on roads in which water is scooped while the locomotive is in motion. Just to the rear of these lugs 42 is the scoop air-cylinder lug 43, adapted to have attached thereto the pneumatic cylinder for raising and lowering the scoop. The particular construction of the scoop and its associated parts forms no part of the present invention, with the exception of the provision of integral parts on the underframe to support the scoop and its mechanism. The underframe is provided with a downwardly and forwardly sloping passage 44 through which the water from the scoop and the external scoop pipe 45 passes to the internal water scoop pipe 45' which is secured to the upper side of the center sill above the surface of the bottom plate of the water tank. The walls of this passage 44 are cast integral with the frame. Ahead of this passage on the left side are the lugs

47' for the attachment of the air brake cylinder.

Extending laterally from the forward center-plate support 21 are the side bearing support arms 46, the upper surfaces of which lie in the same plane as the top surface of the whole center sill so that they form in effect a short forward body bolster to assist the center sill in supporting the tank. Suitable means such as shown at 47 in Fig. 11 are provided for the attachment of the side bearings. At the rear center-plate support 22 similar side bearing support arms 48 are provided which function in the same manner as the front ones to not only support side bearings for the rear truck, but to form a short body bolster for the tank. The center-plate supports 21 and 22 are really formed by the intersection of the center sill with the body bolsters. From the above description it will be seen that the tender underframe comprises in effect only a single center sill, there being absolutely no end sills and no side sills. There are, however, two integral body bolsters, but these are much shorter than the usual body bolsters and extend laterally only a sufficient distance to provide support for the side bearings, and a wider base for the main internal tank bracing.

At the extreme rear of the center sill and just above the draft gear pocket, there is provided a transverse beam 49 for the sole purpose of supporting the rear steps 50. Referring to Figs. 14 and 15 it will be seen that this rear step beam is formed of two channels 51 with their grooves facing outwardly and secured together by the top cover plate 52 suitably riveted thereto. The lower flanges of these channels are riveted to a gusset plate 53 which is substantially triangular in form and best shown in Fig. 14. This gusset plate is received in the depressed portion 54 of the top plate of the center sill, as shown in Fig. 9, to which it is securely riveted to prevent any twisting of the rear step beam. The gusset plate is of such a thickness and the depression 54 of such a depth that the top of the gusset plate is flush with the top surface of the center sill. This step beam is definitely not an end sill, nor is it a rear stop for the tank, for it is spaced rearwardly of the tank approximately one-half inch and hence entirely independent thereof. At the front end there is absolutely no transverse member.

In order to provide a cushion for the tank and to take up slight irregularities in the top surface of the center sill, cushion strips are secured to the sill throughout its length. These cushion strips comprise longitudinally extending wood members 55 having their edges in the same plane as the sides of the center sill and slightly spaced

apart along the longitudinal center of the sill as best shown in Figs. 3, 4 and 5. Over the side bearing support arms are similar blocks of wood 56 to provide support for the tank clear to the ends of these arms. These blocks may best be seen in Figs. 4, 10 and 12.

The upper surfaces of the center sill, the center-plate supports and the side bearing support arms lie in the same horizontal plane 2 and the cushion blocks and strips are all of the same thickness in order that the underframe may support the tender tank 57 which has a flat or plane bottom 58.

15 The tender tank externally is of the conventional shape and is substantially rectangular in transverse cross section. It contains the water tank or compartment 59 and the coal compartment 60 which is at the 20 front end so as to be readily accessible to the locomotive. This coal compartment is separated from the water tank by the slope sheet 61, the construction here differing slightly from the conventional in that the 25 slope sheet extends clear to the side plates or members 62 of the tank and is rigidly secured thereto as shown at 63 in Fig. 7. The forward portion of the tank adjacent the coal compartment has its sides turned inward near the top as shown at 64, and the slope sheet extends above and is secured to these inturned portions as shown at 65. The rear portion of the whole tank is lower than the front portion in order to retain the 30 center of gravity as low as possible in the section containing the water, which is, of course, the heavier.

The side members 62 or plates of the tank extend the full length of the same and are 40 reinforced in various places throughout their length by vertical stiffeners 66 to prevent buckling. These stiffeners may be in the form of angles or T-bars either riveted or welded to the inner surfaces of the side 45 plates as best shown in Figs. 3, 4, 5, 6 and 7. Being secured to the top plate 67 and the bottom plate or water bottom 58 of the tank, the side plates act to some extent as longitudinal vertical girders preventing any 50 fore and aft sagging of the top and bottom plates under the load. Transverse sagging is prevented in two ways. First by the slope sheet and rear end plate 68, and second by internal bracing members which will be 55 later described.

The slope sheet 61 by virtue of being extended and secured to the side plates, as disclosed in Fig. 7 at 63, acts as a transverse girder to support these side plates from the 60 portion of the water bottom of the tank which rests upon and transfers the load to the center sill. The lower edge of the slope sheet is supported by the transverse partition wall 69 which separates the stoker feed screw compartment 70 from the water tank to the

rear of it. This compartment 70 is further isolated from the water tank by means of the longitudinal walls 71 secured at the rear to the partition wall 69 and running forward and being secured to the front sheet 70 sections 72 which close the forward end of the tank. The upper edges of the walls 71 are secured in a watertight manner to the coal compartment side feed plates 73 which extend from the front walls 72 rearwardly 75 and are joined to the slope sheet at 73. These side feed plates together with the slope sheet tend to direct the coal onto the diaphragm 74, from whence it passes through the longitudinal slot 75 in this diaphragm and into the conveyer screw pocket 70. The construction and operation of the conveyer and stoking apparatus form no part of the present invention and have neither been shown in the drawings nor described in this specification.

The side coal feed plates 73 are reinforced on their under sides by the angle stiffeners 76, certain of which are continued downwardly along the outer faces of the longitudinal walls 71, as shown at 77, to provide added strength. Gussets 78 connect the side coal feed plates 73 to the portions 63 and 64 of the side plates of the tank to reinforce them where there is no top plate for that purpose, i. e. at the coal compartment.

To transfer the load of the tank and in the tank to the center sill and to the center-plate supports and side bearing support arms without relying on the water bottom as a transverse beam, resort is had to internal bracing members or struts which are best disclosed in Figs. 3, 4, 5 and 6. Over the rear center-plate support 22 are arranged the cast steel struts 79 which transfer the load from near the rear ends of the side plates 62 of the tank to the center sill and rear center-plate support as best disclosed in Fig. 4, where it will be seen that these members 79 are secured to the top plate 67 and to the side plates 62 as at 80 and to the water bottom directly over the center-plate support. No additional support is needed intermediate the center sill and the edge of the bottom near this section, owing to the lateral arms which support the side bearings and serve also as short body bolsters to prevent flexing of the water bottom.

At intermediate sections such as those disclosed in Fig. 5, where there are no lateral projections from the center sill, the internal bracing takes the form of a pair of struts on each side of the center sill. One of these, 81, transfers the load from near the center of the unsupported portion of the bottom plate to the top plate at 82, this member 81 being in tension. From the point 82 the load is transferred directly to the center sill by the compression strut 83.

Referring to Figure 6, it will be seen that

the load from the center of the unsupported side portions of the water bottom is transferred by means of tension struts such as 84 to the top plate as at 85. These struts 5 are secured to the top plate just to the rear of the transverse line where it is bent upwardly as shown at 86 to be secured to the slope sheet as at 87. This transverse portion 10 86, which is longitudinally inclined, together with the slope sheet 61 acts as a bolster which transposes the load from the tension struts 84 to the center sill close to where it is provided with the latitudinal projections which are used to support the 15 side bearings for the front truck. The under side of the slope sheet is braced by the struts 88, one on either side of the center, which transfer the weight on the slope sheet to the bottom plate just beyond its support by the 20 center sill and also prevent its buckling due to surging of the water. Still further forward the slope sheet is supported by the transversely and longitudinally inclined struts 89 which meet at the center and are 25 there secured to the bottom plate to transfer the load directly to the center sill from two points arranged substantially one-third of the width of the slope sheet apart. The struts 88 and 89 not only support the load 30 of the coal resting on the slope sheet, but prevent it from buckling while performing its duty as a transverse girder, and also act as a means of transferring certain of the water load placed thereon by the tension 35 struts from the top sheet to the center sill.

The bottom plate or water bottom 58 of the complete tank is of much heavier metal than the side plates since it is subject to a greater load and has secured thereto the 40 various load transferring members. Referring particularly to Figs. 3, 4, 5 and 6, it will be seen that a large part of the load on the bottom plate is transferred directly or indirectly to the center sill, leaving but 45 a small portion to be absorbed by the side plates in their function as longitudinal vertical girders. As previously pointed out, the side plates are supported near the rear not only by the rear plate 68 which rests 50 on the center sill, but by the cast steel bracing members 79. Near the front, the side plates are adequately supported by the transverse girder or bolster formed by the slope sheet and its corresponding reinforcing 55 members. They are also supported by the side coal guide sheets 73 and the conveyer pocket sides 71 which have direct bearing on the short body bolster formed by the side bearing support arms. Thus the side plates act as longitudinal girders to transfer the remaining load by way of transverse girders to the center sill over the center-plate supports.

Referring to Fig. 1, it will be seen that 60 the tank rests freely on top of the center sill,

center-plate supports and side bearing support arms. The bottom plate is cut away beneath the conveyer screw pocket so that the rear edge of this opening together with the transverse plate or wall 69 abuts against 70 the front end tank stops 35 cast integral with the center sill. The length of the tank is so proportioned and the rear step beam 49 so positioned that when the tank is against the front end stops 35, the rear 75 plate 68 is spaced approximately one-half inch forwardly of the step beam which thus has no function in supporting or positioning the tank. The rear end of the tank is secured down and held tightly against the 80 center sill by means of two bolts, one on either side of the center sill. These bolts 90 are best seen in Figs. 3, 14 and 15. Their upper ends are flattened in order that they may be secured by riveting to the end plate 85 68 and to the upturned flange 91 of the water bottom as shown at 92. The bolts pass through apertures in the gusset plate 53 and are threaded to receive the nuts 93 90 to hold the rear end of the tank down.

The front end of the tank is secured to the underframe by the bolts 94 which pass through the flanges 95 of the reinforcing angles secured along the longitudinal edges 95 of the opening in the bottom plate beneath the coal pocket. Each of these bolts is received in a hole 96 formed in the front edge of the corresponding side bearing support arm on its respective side of the center sill 100 and an appropriate nut 97 is threaded onto the bolt to retain the same in position.

The tank is at all times securely drawn forward against the front end stops by means of a pair of longitudinal bolts 98 105 which are best seen in Figs. 10, 11 and 13, one on either side of the center sill. Each of these bolts has a portion of its shank passing between the vertical flanges 99 of a pair of angles 100 which are riveted one 110 on either side of the flange 95 previously mentioned. The rear edges of the flanges 99 are notched as shown at 101 to receive the head of the bolt 98 and to prevent it from rotating. The bottoms of the notches 115 are engaged by the under side of the head of the bolt to transfer the strain from the bolt to the angles and thence to the bottom plate of the tank. The forward end of each bolt passes through a substantially longitudinal aperture 102 cored into the side bearing support arm inside of the opening for the reception of the bolt 94. A nut 103 is threaded onto the bolt 98 and engages against the front face of the side bearing 120 support arm so that upon tightening the nut the tank may be drawn forward securely 125 against the front end stops.

The above described tank and securing means are for tenders equipped with auto- 130

matic stokers. In case the tender is adapted for hand firing of the locomotive several slight modifications may be made. The conveyer screw pocket 70 is eliminated and this 5 space is occupied by a compartment connected to the part of the tank for the reception of the water. For this reason there is no opening or longitudinal slot 104 in the bottom plate and therefore no rear edge of such 10 slot to cooperate with the front end tank stops 35. These stops are therefore removed from the casting to make room for the flat water bottom sheet 105 of the tank as shown in Fig. 16. A closing sheet or front end 15 plate 106 is provided as shown in Figures 16 and 17, and the front face of this sheet together with the forward edge of the bottom plate 105 is adapted to cooperate with the shoulder or abutment 36 formed where 20 the center sill is elevated to receive the front draw bar fulcrums to thus limit the forward movement of the tank under the action of the bolts 98' which are applied and operate in the same manner as just discussed in connection with the stoker type of tank. The 25 forward end of the tank is, however, secured down to the center sill in a different manner, for vertical bolts cannot be applied through the side bearing support arms as 30 will be obvious when it is considered that the conveyer screw pocket 70 is now occupied by water. Therefore, reinforced angle members 107 are securely riveted to the outside of front sheet 106 and their horizontal 35 flanges are bored to receive the bolts 108 which pass down through openings 109 formed in the bosses 110 on the sides of the center sill just to the rear of the front draw bar fulcrums. These openings are best 40 shown in Figs. 8 and 17. To strengthen the meeting corner of the bottom and front plate and to more firmly support the angles 107, an internal supporting strut 111 may be provided having a flange secured behind the 45 angles 107 by the same rivets which hold them in place and having a second flange 112 which is secured to the bottom plate.

The interchangeability of the two forms of tanks with regard to the underframe will 50 be readily apparent. When the frame is used with a stoker type tank, it is provided with two front end tank stops. Of these only the rearmost one, 35, is effective to cooperate with the tank, for the front end of the central portion of the water bottom is cut away and will not contact with the abutment formed by the elevation of the front end of the center sill to accommodate the front draw bar fulcrums. When a tank 55 adapted for hand firing is applied to the underframe, the stops 35 must be removed from the center sill and the abutment then acts as a front end tank stop, for the water bottom extends clear to the front of the tank throughout its full width. This is the only

difference in construction required in the underframe. The bolt holes for receiving the front end holding down bolts occur in each type of frame, and a proper set may be readily selected for use.

From the above description, it will be evident that the present invention consists of a novel and simplified tender and construction wherein the underframe is reduced to a single unitary casting having but a center sill and a pair of transverse members resembling short body bolsters. A novel form of tank has been invented to cooperate with the single center sill and to be supported in such a manner as to eliminate strains on the water bottom due to its large overhang laterally from the center sill. Portions of the water bottom lacking direct support from beneath by the usual underframe parts are adequately supported by internal bracing members indirectly transferring the load to the center sill and the short body bolsters. The construction of the tank is no more complicated than that of the conventional tank, and the weight is substantially the same, whereas the underframe has been materially reduced in both size and weight, and the constructional difficulties encountered in more complex frames have all 80 been eliminated, whereby there is a material reduction in weight of the whole tender and a decrease in the cost of construction of the same. While specific embodiments of the invention have been illustrated and described, it is to be understood that these are only exemplary, and that changes and modification in the same may be made by those skilled in the art without departing from the spirit of the invention as set forth in the following claims.

Having thus described the invention, what is claimed as new and desired to be secured by Letters Patent is:

1. A tender underframe comprising a single center sill and lateral side bearing support arms, said members engaging with and forming the sole support for a tank.
2. A tender underframe comprising a single center sill, center-plates and lateral side bearing support arms, said members engaging with and forming the sole support for a tank.
3. A tender underframe comprising a single center sill, center-plate supports and lateral side bearing support arms, said members engaging with and forming the sole support for a tank.
4. A tender underframe comprising a unitary casting including a single center sill and lateral side bearing support arms extending from said center sill, said members engaging with and forming the sole support for the tender tank.
5. A tender underframe comprising a unitary casting including a single center sill,

center plate supports and lateral side bearing support arms extending from said center plate supports, said members engaging with and forming the sole support for the tender tank.

6. A tender underframe comprising a single center sill of box girder formation, body bolsters formed by side bearing support arms, and means to secure a tank to said frame to be engaged and supported solely by the above mentioned members.

7. A tender underframe comprising a single center sill of box girder formation, center plate supports, body bolsters formed by side bearing support arms, and means to secure a tank to said frame to be engaged and supported solely by the above mentioned members.

8. A tender underframe comprising a unitary casting including a single center sill of girder formation, laterally extending side bearing support arms forming short body bolsters, and means to secure a tank to said frame, said tank being engaged and supported only by said above mentioned members.

9. A tender underframe comprising a single center sill and lateral side bearing support arms, said members engaging with and forming the sole support for a tank, and means forming a draft gear pocket integral with said center sill.

10. A tender underframe comprising a single center sill, lateral side bearing support arms projecting therefrom, center plate supports formed by the intersection of said center sill and arms, said members engaging with and forming the sole support for a tank, and means forming a draft gear pocket integral with said center sill.

11. A tender underframe comprising a single center sill and side bearing support arms, the top surfaces of said parts all lying in the same plane to engage and serve as the sole supporting means for a tender tank.

12. A tender underframe comprising a single center sill, center-plate supports and side bearing support arms, the top surfaces of said parts all lying in the same plane to engage and serve as the sole supporting means for a tender tank.

13. A tender underframe formed as a unitary casting including only a center sill of hollow box girder formation, means at each end thereof forming draft gear pockets, and short arms projecting laterally from said center sill to support side bearings.

14. A tender underframe formed as a unitary casting including a single center sill, center-plate supports, side bearing support arms, draft gear attaching means and brake cylinder attaching means, said center sill and arms engaging and forming the sole supporting means for a tender tank.

15. A tender underframe formed as a uni-

tary casting including a single center sill having upper and lower plates, center-plate supports, side bearing support arms, draft gear attaching means, means on the lower plate of said center sill to receive a brake reservoir, and a tank front end stop integral with the upper plate of said sill for the purpose described.

16. A tender underframe comprising a unitary casting including a single center sill of box girder formation, center-plates, side bearing support arms forming short body bolsters, draft gear attaching means at each end of said sill, brake cylinder attaching means on said sill, a tank front end stop, a water duct and means on said center sill to support a water scoop and operating mechanism.

17. A tender underframe comprising a unitary casting including a single center sill of box girder formation, center-plates, side bearing support arms forming short body bolsters, draft gear attaching means at each end of said sill, brake reservoir attaching means on said sill, a tank front end stop, and means on said center sill to support a water scoop and operating mechanism.

18. A tender underframe comprising a unitary casting including a single center sill of box girder formation, center-plates, side bearing support arms forming short body bolsters, draft gear attaching means at each end of said sill, brake cylinder and reservoir attaching means on said sill, a tank front end stop, and means on said center sill to support a water scoop and operating mechanism.

19. A locomotive tender comprising a tank and an underframe, the sole supporting means engaging said tank being a center sill and two short transverse members forming parts of the underframe.

20. A locomotive tender comprising an underframe and a tank, having a flat water bottom, said underframe engaging and supporting said water bottom and tank solely along its longitudinal center for a width less than one-half of the width of said bottom.

21. A locomotive tender comprising an underframe and tank, said underframe including a center sill and side bearing support arms forming the sole support for said tank, and bracing means in said tank to transfer substantially all of the load therein indirectly to said underframe.

22. A locomotive tender comprising an underframe and a tank, said tank having a water bottom, means on said underframe to support said water bottom over a portion of its area, and means to transfer the load on the unsupported area indirectly to the supported area.

23. A locomotive tender comprising an underframe and a tank, said underframe in-

cluding a single center sill and two short transverse body bolsters formed by side bearing support arms, said tank having a water bottom supported solely by said center sill and body bolsters, and internal bracing in said tank to transfer the load of and in said tank to said center sill and bolsters.

24. A locomotive tender comprising an underframe and a tank, said underframe including a single center sill and two short transverse body bolsters formed by side bearing support arms, said tank having a water bottom supported solely by said center sill and body bolsters, side plates secured to said water bottom, and means supporting said side plates from said frame whereby they act as longitudinal girders.

25. A locomotive tender comprising an underframe and a tank, said underframe including a single center sill and two short transverse body bolsters formed by side bearing support arms, said tank having a water bottom supported solely by said center sill and body bolsters, and means within said tank to indirectly transfer the load of and on said water bottom to said underframe.

26. A locomotive tender comprising an underframe and a tank, said tank including a water bottom, side plates, a slope sheet and an end sheet, said slope sheet being extended and secured to the side plates, said end sheet being secured to said side plates, means on said underframe to support said tank substantially solely along the longitudinal center of said water bottom, and means supporting said slope sheet from the supported portion of said water bottom, for the purpose described.

27. A locomotive tender comprising an underframe and a tank, said tank including a water bottom, side plates, a slope sheet and an end sheet, said slope sheet being extended and secured to the side plates, said end sheet being secured to said side plates, means on said underframe to support said tank water bottom for a small portion of its area, and means whereby said slope sheet is supported from the supported area of the water bottom for the purpose described.

28. A locomotive tender comprising an underframe and a tank, said tank including a water bottom, side plates, a slope sheet and an end sheet, said slope sheet being extended and secured to the side plates, said end sheet being secured to said side plates, means on said underframe to support said tank substantially solely along the longitudinal center of said water bottom, means supporting said slope sheet from the supported portion of said water bottom, means supporting said end plate from the supported portion of said water bottom whereby the side plates are caused to act as longitudinal girders.

29. A locomotive tender comprising an un-

derframe and a tank, said tank including a water bottom, side plates, a slope sheet and an end sheet, said slope sheet being extended and secured to the side plates, said end sheet being secured to said side plates, means on said underframe to support said tank water bottom for a small portion of its area, means supporting said slope sheet from the supported portion of said water bottom and means supporting said end plate from the supported portion of the water bottom whereby the side plates are caused to act as longitudinal girders.

30. A locomotive tender comprising an underframe and a tank, said tank including a water bottom and side plates secured thereto, said underframe including a center sill forming substantially the sole support for said tank, said water bottom resting thereon, means near one end of said tank forming therewith, in effect, a transverse body bolster supported from the portion of the water bottom resting on said center sill, and braces near the other end of said tank supporting said side plates from the portion of the water bottom above said center sill.

31. A locomotive tender comprising an underframe and a tank, said tank including a water bottom, side plates secured thereto and a top plate secured to said side plates, said underframe supporting said water bottom solely along a central longitudinal strip, a pair of struts secured to said bottom within the supported area, said struts diverging and being joined to said top sheet, and a strut depending from each junction with the top sheet and being secured to said bottom sheet between the supported area and said side plates, for the purpose described.

32. A locomotive tender comprising an underframe and a tank, said tank including a water bottom, side plates secured thereto and a top plate secured to said side plates, said underframe supporting said water bottom solely along a central longitudinal strip, a compression strut supporting said top plate from the supported area of said water bottom, and a tension strut connecting an unsupported portion of said water bottom to said top plate adjacent the junction of said compression strut and top plate for the purpose described.

33. A locomotive tender comprising an underframe and a tank, said tank including a water bottom, side plates secured thereto and a top plate secured to said side plates, said underframe supporting said water bottom under only a small portion of its area, a compression strut supporting said top plate from the supported area of said water bottom, and a tension strut connecting an unsupported portion of said water bottom to said top plate adjacent the junction of said compression strut and top plate for the purpose described.

34. A locomotive tender comprising an underframe and a tank, said underframe including a single center sill, center-plates and side bearing support arms, said tank including a water bottom supported solely by the above parts of said underframe, side plates secured to said water bottom, and a top plate secured to said side plates, means intermediate the ends of said tank supporting the side plates and top plate from the supported portion of said water bottom for the purpose described. 5
35. A locomotive tender comprising an underframe and a tank, said underframe including a single center sill, center-plates and side bearing support arms, said tank including a water bottom supported solely by the above parts of said underframe, side plates secured to said water bottom, and a top 10 plate secured to said side plates, means intermediate the ends of said tank supporting the side plates and top plate from the supported portion of said water bottom, and means supporting portions of said water 15 bottom, beyond said underframe support, from said top plate. 20
36. A tender tank including in combination, a water bottom, side plates secured to the edges thereof, a slope sheet secured directly to said side plates, and means to support said slope sheet from said water bottom for the purpose described. 30
37. A tender tank including in combination, a water bottom, side plates secured to the edges thereof, an end plate secured to said water bottom and side plates, a slope sheet secured directly to and supporting said side plates and supported from said water bottom, a top plate secured to said side plates, end plate and slope sheet, and means 35
- to support said side plates from the longitudinal center of said water bottom. 40
38. A locomotive tender including a tank and an underframe, said underframe having a single center sill, a transverse step beam secured to one end of said sill, a gusset plate connecting the overhanging portions of said beam to said sill, said tank having a bottom plate resting on said sill and gusset, an end plate for said tank secured to said bottom 45 plate, and means securing said end plate to said gusset plate. 50
39. A locomotive tender including a tank and an underframe, said underframe including a single center sill, a tank front end stop thereon, a transverse step beam secured near one end of said sill, a gusset plate forming a part of said beam and securing it to said sill, said tank having a bottom plate resting on said sill and gusset plate, a rear end plate 55 secured to said bottom plate, means drawing said bottom plate into engagement with said front end stop and away from said beam, and means securing said rear plate to said gusset for the purpose described. 60
40. A locomotive tender including in combination, an underframe and a tank, said underframe including a single center sill and side bearing support arms, a front end tank stop on said sill, said tank including a water 70 bottom resting on said sill and arms, means secured to said water bottom and passing horizontally through said arms to draw said tank against said stop, and means passing vertically through said arms to secure said water bottom thereto. 75

In testimony whereof I hereunto affix my signature.

WILLIAM F. KIESEL, Jr.
